UNITED STATES PATENT OFFICE.

JOHN CORYDON GIBBS, OF LANCASTER, PENNSYLVANIA.

SIFTER CAN.

Application filed July 25, 1921. Serial No. 487,226.

To all whom it may concern:

Be it known that I, JOHN CORYDON GIBBS, a citizen of the United States, residing at Lancaster, county of Lancaster, State of Pennsylvania, have invented certain new and useful Improvements in Sifter Cans, of which the following is a specification.

This invention has relation to that type of sifter boxes, in which the original retail package is arranged to be used as a sifter box, and particularly to that class of boxes in which the top wall of the box is depressed below an upstanding corner bead, as more fully hereinafter set forth.

15 In the drawing:—

Fig. 1 is a perspective of my improved box;

Fig. 2 is a plan view showing the dredger-plate adjusted for sifting;

20 Fig. 3 is a similar view showing the plate adjusted for filling or emptying;

Fig. 4 is a sectional view on the line 4—4 of Fig. 2.

In the drawing, 10 designates the top wall 25 of the can, which is, as usual in this type of can, set below the top edge of the continuous corner bead 11. This top wall is provided with a filling and emptying opening 12 near one end of the can, and with an up- 30 standing stop 13 near the other end, this stop being formed by interiorly indenting the top wall.

Slidably mounted upon the top wall is a plate 14, which fits close against the top wall and is adapted to slide between the stop 35 13 and the bead at the opposite end of the can top. This plate is slidably affixed to the can top by upstanding hooks 15, which engage over the beads at the opposite side 40 edges of the can, these hooks being virtually channels formed integral with the plate 14, the shape of the hooks being such as to closely grasp the over-hanging bead and thus securely hold the plate to the can, 45 closely against the upper face of the top of the can.

The dredger plate 14 is provided with a series of perforations 16 near one edge, and at its other edge it is provided with an up-standing tab 17 by which it may be manipulated, although this plate may be slid back and forth by grasping the bead hooks 15.

The operation of the device is apparent from the foregoing when taken in connection with the various figures. It will be observed that I provide the combined sifting and pouring box that is exceedingly simple in construction. It will be observed that my construction renders it unnecessary to provide an upstanding neck in the top wall of the box, and it will be further observed that neither in its sifting position nor in its pouring position does the plate project beyond either end of the box top. It will be observed also that my construction avoids any 65 projections extending above the top edge of the box, thereby contributing to economy in packing and shipping.

I claim:—

The combination with a box whose top 70 wall is provided with a filling and emptying opening at one end and with an upstanding stop near its other end, said top wall being depressed below the corner bead, and a dredger plate provided with perforations 7 near one end and also with upstanding channel-like hooks at its opposite edges slidably grasping the beads at the side edges of the top and shaped to hold the dredger plate down on the top wall, the length of the 8 dredger-plate being such that when it is adjusted against the stop the filling-opening will be uncovered.

In testimony whereof I hereunto affix my signature in the presence of two witnesses. 85

JOHN CORYDON GIBBS.
